DESIGN FOR A DRESS

Francis X. Sinnott, New York, N. Y.

Application February 25, 1938, Serial No. 75,394

Term of patent 3½ years

To all whom it may concern:

Be it known that I, Francis X. Sinnott, a citizen of the United States, residing at 145 West 55th Street, in the county of New York and city and State of New York, have invented a new, original, and ornamental Design for a Dress, of which the following is a specification, reference being had to the accompanying drawing, constituting a part thereof:

Fig. 1 is a front view of the dress.

Fig. 2 is the rear view of the dress showing my new design as shown in Fig. 1.

The characteristic feature of my dress resides in the specific arrangement of the Shirred ruching upon the sleeves, shoulders, neck and hem of the garment, as shown in association with V-shaped pleating above the waistline as shown.

I claim:

The ornamental design for a dress substantially as shown and described.

FRANCIS X. SINNOTT.
